UNITED STATES PATENT OFFICE.

JOHN GRANT, OF CHICAGO, ILLINOIS.

MOVING-PICTURE MACHINE.

1,225,801.

Specification of Letters Patent.

Patented May 15, 1917.

Application filed September 9, 1913. Serial No. 788,857.

To all whom it may concern:

Be it known that I, JOHN GRANT, a citizen of the United States, residing at Chicago, in the county of Cook and State of Illinois, have invented certain new and useful Improvements in Moving-Picture Machines, of which the following is a specification.

This invention relates to improvements in moving picture machines and has for its object to provide an improved form of machine in which danger of combustion of the film is practically eliminated.

The object of my invention is to provide an improved fire shutter which will automatically open when the film is being driven and which will automatically close when the same is stopped. It is often the case that a film ignites from the heat of projected light rays, owing to the operator having neglected to close the fire shutter, and to overcome this objection I have devised my improved fire shutter and operating means.

I obtain these and other results by the structure described and shown in the following specification and accompanying drawings, in which:

Figure 1 is a side elevation of a machine embodying my invention;

Fig. 2 is a front elevation of the same;

Fig. 3 is a cross section along the line 5—5 of Fig. 2;

Fig. 4 is a horizontal section along the line 6—6 of Fig. 3;

Fig. 5 is a perspective detail of the operating handle;

Fig. 6 is a similar detail of the operating crank end;

Fig. 7 is a detail of the spring member;

Fig. 8 is a detail of the fire shutter operating lever.

Like characters refer to like elements throughout the drawings, in which;

10 indicates the usual form of casing having the supporting legs or pedestal 11 adapted to be bolted or otherwise secured to a table or the like. This casing 10 is provided with the front wall 12 having the usual light opening or aperture 13 therein. The shaft 24 extends through the casing 11, as clearly shown in Fig. 4, and is adapted to be engaged at its outer extremity by an operating handle, as will be described hereinafter. A protecting and guiding plate 25

is provided in front of and spaced from the wall 12 of the casing 10, this plate or apron 25 being outwardly turned at its upper portion, as indicated, at 25^a forming a guiding means for the film 17. The plate or apron 25 is provided with the arms 25^b pivotally mounted at their outer extremities to the casing 10, as indicated by numeral 25^c, whereby the entire plate may be pivoted out of position shown. The plate is formed with the tab or lug 25^d projecting outwardly at one side therefrom and the thumb screw 26 is mounted on the front wall 12 of the casing 10 to engage the tab 25^d when it is desired to hold the plate 25 in position. The casing 32 normally covers the members of the Geneva movement, as indicated in Fig. 1, so that the same may be run in oil if so desired. The shaft 29 carries at its other extremity the pinion 33 which is driven by the gear 34 mounted upon the shaft 35 which in turn carries the smaller pinion 36 driven from the main driving gear 23. A fly-wheel 37 is carried at one extremity of the shaft 29 outwardly of the pinion 33 and serves to accomplish the usual function of such an element in maintaining the speed of rotation approximately constant. Intermediate of the pinion 33 and fly-wheel 37 is a sprocket 38 serving to drive a chain 39 which also passes around the smaller sprocket 40 mounted on a shaft 40^a (see Fig. 1). Located below the shaft 29 a considerable distance, is the roller 41 pivotally mounted upon the shaft 42 which projects angularly from the lever or arm 43. The cotter-pin or the like 44 serves to prevent side movement in one direction of the roller 41, the shaft 42 being enlarged at 42^a to form a shoulder to prevent lateral movement of the roller 41 in the other direction. The casing 10 is provided with the outwardly extending portion 10^a below the Geneva movement and a bolt or stud 46 projects therefrom being headed at 46^a in carrying a nut at 46^b, as clearly shown in Fig. 2. The arm lever 43 is provided with the slotted portion 43^a intermediate its extremities, this slotted portion being slightly curved to conform to the circular movement of the arm 43, the bolt 46 extending through the slotted portion 43^a. A collar or washer 47 is maintained in close contact with one side of the arm 43 adjacent the slot 43^a by means of the spring 48 coiled around the 110

bolt 46 and extending between the head 46^a and the said washer 47. The frictional contact between the washer 47 and the side of the arm 43 will serve to maintain the latter in adjusted position with respect to the casing 10 as will be apparent. The arm 43 terminates in the handle portion 43^c and it is apparent that engagement of the latter to move the arm 43 about its pivotal mounting at 44 will serve to raise or lower the roller 41 for the purpose to be herein-after described. A spring 68 extends between the pivotal mounting 67 and the arm 66 serves to maintain the roller 64 in yieldable engagement with the sprocket 63.

The plate or apron 25 is provided with the outwardly extending lugs 25^h above the opening 25^e and a rod 25^j passes therebetween and is pivotally mounted therein. Secured to this rod between the lugs 25^h is the fire shutter 90 adapted to close the opening 13 to prevent ignition of the film by the heat or light rays should the same be standing still during non-operation. The rod 25^j is extended outwardly at one side and is bent upwardly at 25^k and then outwardly at right angles thereto, as indicated by numeral 25^m.

The shaft 24 extends outwardly through one side of the casing 10 through the bearing portion 10^b. Outwardly thereof a collar 24^a is secured to the shaft by a pin 24^b or the like. This collar is recessed at 24^c around the shaft 24 and a coil spring 91 is located therearound having the bent end 91^a fixed to the collar 24^a as shown in Fig. 4. The handle 92 is provided with the hub portion 92^a adapted to be fitted over the end of the shaft 24, as described below. The shaft 24 is provided with the pin 93 extending transversely therethrough outwardly of the collar 24^a. The hub 92^a of the handle is centrally apertured at 92^b to fit over the shaft 24 and is transversely slotted, as indicated by numeral 92^c, the slots being constructed to slightly converge toward the center of the hub portion, as clearly shown in Fig. 5. The hub portion is further provided with a small hole 92^d adapted to engage the other bent end 91^a of the spring 91 when in assembled position. At its outer periphery the hub portion 92^a is grooved, as indicated by numeral 92^e and a spring member 94, (see Fig. 7) provided with the curved portion 94^a with the bent end 94^b is adapted to be located in the groove, as shown in Figs. 3 and 5, with its bent end 94^b extending into slotted portion 92^c. A collar 95 is slidably mounted upon the hub portion 92^a of the handle 92, as shown in Figs. 3 and 4 over the spring member 94. Secured to this collar to rotate therewith, is the looped portion 96^a of the lever 96, which is slightly curved or flared at its outer extremity. This lever is adapted to

coact with the angularly bent portion 25^m of rod 25^j, as will be hereinafter described. The operation of the same is as follows:—

After the handle 92, together with the collar 95 has been slipped over the rod 24, in which position it may be secured by a screw or the like, threaded into the end of the said shaft, the transverse pin 93 will fit in the slotted portion 92^c of handle 92, as clearly shown in Fig. 3. Upon rotation of the handle the shaft 24 will be rotated to operate the film. Simultaneously the hub portion 92^a of the handle will operate, when rotated in the direction of the arrows, (see Fig. 3) to press the bent end 94^b of the spring 94 against the transverse pin 93, thereby serving to press the bent portion 94^a of the spring outwardly to frictionally engage the collar 95. This frictional engagement is such as to cause the collar 95 to rotate with the handle 92. At the same time the lever 96 will move upwardly with the collar until it strikes the portion 25^m of the rod which it will carry upwardly to position shown in Fig. 3 at the same time raising the fire shutter to the position shown therein. The fire shutter 90 will be maintained in open position so long as the handle is rotated and the machine operated, owing to the frictional contact described. As soon as the handle is stopped, however, so that the film stops, the collar 95 will slip relative to the hub portion 92^a owing to the weight of the raised lever arm 96, which will fall back to permit the fire shutter to close until the machine is again in operation, thereby protecting the film from the concentrated heat and light rays while it is standing still.

It will be apparent from the above that I have provided a construction which will attain the results set forth in the preamble to this specification.

While I have shown and described a specific embodiment of my invention, I do not wish to be restricted to such showing and description beyond the scope of the appended claims.

What I claim is:—

1. In a device of the class described having an opening, a shutter for said opening, said shutter having an arm, means to drive a film or the like, said means comprising a shaft, a hub member adapted to be mounted upon and engage said shaft, a lever having a portion mounted to slip upon said hub portion, means associated with said hub to rotate the same together with said shaft and means to frictionally engage said lever with said hub upon rotation thereof, whereby said lever will be actuated to coact with said shutter arm and thereby open said shutter and maintain the same in open position during the operation of said driving means.

2. In a device of the class described, a

fire shutter, a rotatable shaft, a pin or the like carried by said shaft, a hub member mounted on said shaft and engaging said pin, a collar loosely mounted on said hub and operatively associated with said shutter, and a friction-producing means having a portion interposed between said hub and pin and operable upon rotation of said shaft by said hub to engage said collar and rotate 10 the same to open said shutter.

3. In a device of the class described, a fire shutter, a rotatable shaft, a pin or the like carried by said shaft, an operating handle having a hub split to engage said 15 pin and fitting around said shaft, a collar loosely fitting around said hub, means car-

ried by said collar to operate said shutter, and a friction-producing member having a portion partially fitting between said hub and collar and a portion fitting between said hub and said pin, said member being arranged and constructed so that proper rotation of said handle will effect frictional engagement between said collar and hub to open said shutter. 20

In testimony whereof, I have subscribed my name.

JOHN GRANT.
